UNITED STATES PATENT OFFICE.

JOHN BLACK, OF HULATT, BRITISH COLUMBIA, CANADA.

VALVE FOR INTERNAL-COMBUSTION ENGINES.

1,382,053.

Specification of Letters Patent. Patented June 21, 1921.

Application filed April 15, 1920. Serial No. 374,109.

To all whom it may concern:

Be it known that I, JOHN BLACK, a subject of the King of Great Britain, and a resident of Hulatt, in the Province of British Columbia, Canada, have invented certain new and useful Improvements in Valves for Internal-Combustion Engines, of which the following is a specification.

My invention relates to improvements in valves for internal combustion engines, and the object of my invention is to provide a valve the use of which insures a positive opening and closing of the valve at all engine speeds and the motion of which is continuous and silent, which is simple in construction and capable of thorough lubrication without danger of flooding the cylinder with lubricant, and which is adapted for use with equal facility in both liquid or air cooled engines.

I attain this object by the construction illustrated in the accompanying drawings in which—

Figure 1 is a vertical section through the assembled valve and contiguous parts.

Fig. 2 is a sectional plan view taken on the line 2-2 of Fig. 1.

Fig. 3 is a plan view of the valve.

Fig. 4 is a view illustrating a modified valve arrangement.

Similar figures of reference indicate similar parts throughout the several views.

1 indicates the upper end of an internal combustion engine cylinder on which is secured a casting 2, provided with a downwardly inwardly tapering annular valve seat 3, having inlet and exhaust ports 4, and 5 respectively, and a hollow central frustoconical vertical stem portion 6 having a port 6^a or passage cut through it, in which valve seat and on the stem is rotatably mounted a cylindrical downwardly inwardly tapering ring valve 7 also having a port 7^a cut through it, as shown in Figs. 1 and 2, the lower edge of which port is spaced a short distance from the foot of the valve. This valve 7 is a grinding fit in the seat 3 and is supported and driven by a gear 8 to which it is attached by means of screws 10, the gear 8 being rotatable in a seat 11 formed in the casting 2, adjustment of the valve 7 being effected by the insertion of shims 12 placed between the gear and the valve.

55 The gear 8 is rotated once for each two revolutions of the crank shaft and is in turn

driven by a pinion 13 mounted on a shaft 14 carried in bearings arranged in any convenient manner. A cover plate 15 for the gear 8 is provided to hold the same in place, the cover being centered by the projection thereinto of the upper end of the stem portion 6, which is reduced as at 16, and the cover is secured to the casting by the screws 17 as shown and is adjusted so that clearance for the rotation of the gear may be obtained by means of shims 18 inserted between the cover and the casting 2.

The valve in Fig. 2 is shown just as it reaches the point of full opening of the exhaust, the valve port 7^a then registering with the stem or seat port 6^a and exhaust port 5 and the width of the exhaust port is equal to 57 $\frac{1}{2}$ ° of a circle having a predetermined radius. The inlet port 4 is closed and has a width equal to 40° of the circle, while the distance between the exhaust port and the inlet port is equal to 62 $\frac{1}{2}$ °. This spacing gives, in degrees of crank shaft travel, a period of 235° between the opening and closing of the exhaust port, being a lead of 45° and a lag of 10°, following which there is an entirely closed period equal to 5°, then a period of 200° between opening and closing of the inlet, a lag of 15° past top dead center and a lag of 35° past bottom dead center and then a closed period during compression and power strokes of 280°. The foregoing spacing or "timing", is used merely for the purpose of illustration; any other suitable "timing" may be employed, according to the requirements of the particular type of engine.

Lubrication of the valve is obtained by providing in its upper end channels 19 and 20, which are interrupted as at 21, as shown in Fig. 3, so as not to supply oil to the channels 22 when these latter channels, which are cut in and extend downwardly in the valve seat 3, are opposite the valve port, the interrupting portion 21 forming a gate, as it were, between the oil channels 19 and 20 and the channels 22. A channel 23 is cut around the lower inner periphery of the valve seat, from which a drilled hole 24 extends to the outside of the casing, for the purpose of draining off the surplus oil, the hole 24 being suitably connected to the main oil sump. It will of course be understood that the oil channels are supplied with oil from the main oil pump with which the engine is provided.

25 indicates a threaded bore in the upper end of the vertical stem portion into which a suitable spark plug is screwed, and to deflect the force of the hot exhaust gases from 5 the spark plug a projection 26 is formed in the bore of the stem below and adjacent the lower end of the bore 25.

27 indicates water jacket space, and 28 10 the outlet for connection to a suitable manifold.

The valves are mounted in pairs, each one of which revolves oppositely to the other, their intake ports opening into the same chamber, however, so that both valves would 15 be served by the same branch of the intake manifold. Each valve has a separate exhaust port and connection to the exhaust manifold.

A modified arrangement is shown in Fig. 20 4 to illustrate the position of the threaded bore for receiving the spark plug when the latter is placed at the side so as to allow the driving shaft to be placed directly above 25 the valves and enables all the valves to be driven by one shaft. In this arrangement the projection 26 is omitted.

From the foregoing it will be seen that I have devised a valve for internal combustion

engines which is highly practical in 30 operation, simple in construction, and adapted to be assembled or disassembled, with great facility and convenience, which is noiseless, capable of easy lubrication, and the use of which insures great economy in 35 the operation of the engine.

What I claim as my invention is:

In an internal combustion engine, a cylinder head having an inlet and an outlet port and a valve seat through which said ports extend, a hollow stem disposed centrally of said valve seat having a port through which communication between said inlet and outlet ports respectively and the engine combustion chamber may be established, said stem having a threaded bore 45 through its upper end, and its inner periphery provided with a deflecting projection adjacent the lower end of said bore, a single ported valve rotatably mounted in said valve seat and on said stem, and a gear 50 secured to the upper end of said valve rotatable therewith.

Signed at Prince George, B. C., Canada, this 30th day of March, 1920.

JOHN BLACK.
